Zugelter & Zugelter
Atty.

embodiment 6-1 right after the date above given will suffice to show that the claims to be granted should be limited to the claims in the present application and not those in the application filed on Jan. 20, 1950, and that the claims in the application filed on Jan. 20, 1950, should be limited to the claims in the present application.

UNITED STATES PATENT OFFICE

2,678,142

MOUPTHPIECE FOR BOTTLES
William J. Creed, Cincinnati, Ohio

Application September 7, 1951, Serial No. 245,576

(Cl. 215—100)

3 Claims. (1) 10 (2) 20 (3) 30

This invention relates to a mouthpiece or spout for a bottle. More particularly, this invention relates to a removable mouthpiece which can be attached to the mouth of a bottle after the cap of the bottle is removed to cover the edge of the mouth of the bottle and thereby protect one while drinking the contents, against being cut by any ragged or sharp edge that may be present. An object of this invention is to provide a removable mouthpiece for a bottle which covers the edge or lip at the mouth of the bottle so that the user can drink out of the bottle without touching the glass thereof when drinking from the bottle.

Glass bottles often have imperfections, small cracks at the mouth, and sometimes sharp edges resulting from chips. A further object of this invention is to provide a protective mouthpiece for a bottle to cover any imperfections, sharp edges or cracks at the mouth thereof and to protect the mouth of the user against injury therefrom.

A further object of this invention is to provide a mouthpiece having a trough-like tongue from which the user can drink, the liquid discharging from the bottle flowing along the trough.

The above and other objects and features of the invention will in part be apparent and will in part be obvious from the detailed description and the drawing, in which:

Figure 1 is a plan view of a blank from which a mouthpiece constructed in accordance with this invention may be formed.

Fig. 2 is a perspective view of a mouthpiece constructed from the blank illustrated in Fig. 1;

Fig. 3 is a view in transverse section showing a bottle with the mouthpiece of Figure 2 mounted thereon;

Fig. 4 is a perspective view showing a mouthpiece constructed in accordance with another embodiment of this invention;

Fig. 5 is a view in section, taken along a line V—V in Fig. 4;

Fig. 6 is a view in section taken along the same line as Fig. 5, but showing the mouthpiece in the position assumed when the mouthpiece is mounted on a bottle;

Fig. 7 is a view in transverse section showing the mouthpiece of Figs. 4-6 mounted on a bottle;

Fig. 8 is a fragmentary view in transverse section, of a bottle equipped with a mouthpiece constructed in accordance with a further embodiment of this invention;

Fig. 9 is a perspective view showing a mouthpiece constructed in accordance with a further embodiment of this invention;

Fig. 10 is a perspective view showing a bottle on which is mounted a mouthpiece constructed in accordance with a further embodiment of this invention; and

Fig. 11 is a view in transverse section showing the bottle and mouthpiece of Fig. 10.

In the following detailed description and the drawing, like reference characters indicate like parts.

- 10 The mouthpiece illustrated in Figs. 2 and 3 is formed from a blank of the type illustrated in Fig. 1. This blank includes a main portion 12, a pair of outwardly extending wings 13 and 14 projecting on opposite sides of the main portion 12, and a tongue 16 projecting in a direction transverse to the wings 13 and 14. Tongue 16 is folded on a fold line 17 flatwise against the main portion 12. Then the blank is shaped so that the lower part of the main portion forms a cylinder 17' as shown in Fig. 2. Cylinder 17' fits inside the mouth of a bottle 17" as shown in Fig. 3. The upper part of the main portion 12 of the blank and wings 13 and 14 are folded into an annular ferrule or ring 18 of channel section. The ring or ferrule fits over and embraces the mouth of the bottle, while the tongue projects parallel to but spaced from the axis of the bottle and cap. Tongue 16 is shaped to form a trough along which fluid can flow from the bottle. When in use, the bottle is tilted to approximately the position shown in Fig. 3, whereupon, the contents of the bottle flow out through the mouth thereof and along the tongue. The user can drink directly from the tongue and the user's mouth need not touch any portion of the glass of the bottle. Thus, the mouthpiece permits sanitary drinking direct from the bottle.

As shown in Figs. 1 and 2, a small opening 18' is provided at the top edge of the ferrule at the center of the tongue. This opening permits drainage of any small amount of liquid which may pass between the cylinder 17' and the wall of the bottle. Any liquid which passes therebetween is discharged through opening 18' and onto the tongue 16 along with the rest of the liquid issuing from the bottle.

As shown in Fig. 2, ferrule 18 and the cylinder 17' are split as indicated at 19, so that, when the mouthpiece is mounted upon a bottle, the edges of the split can be advanced toward each other. The split gives spring action to the ferrule 18 whereby it can be snapped on or off the bottle. When the ferrule 18 is mounted on the bottle, the ferrule engages the mouth of the bottle and cylinder 17' is inside of and firmly engages the interior of the bottle.

The mouthpiece may be made from the type of paper or paperboard used in forming drinking cups. Such material is sufficiently resilient to hold the ferrule and cylinder firmly in engagement with the walls and mouth of the bottle.

In Figs. 4-7 inclusive is shown a device which includes a ferrule 21 and a tongue 22. Ferrule 21 and tongue 22 are formed as separate pieces. Ferrule 21 includes an inner flange or cylinder 23 which fits inside a bottle 24 as shown in Fig. 7, and also an annular ring 26 of channel shape. Ring 26 embraces and fits over the mouth of the bottle 24. The ferrule 21 is provided with a split 26'. Tongue 22 overlies the split. The tongue is attached to ferrule 21 by staples 27 or the like, provided on opposite sides of the split. As shown in Fig. 5, tongue 22 normally is substantially in flatwise engagement with the outer flange of ferrule 21. However, when the edges of the split 26 are urged together to the position shown in Fig. 6, as when the mouthpiece is mounted on the bottle, tongue 22 is separated from the ferrule at its center by a short space 28. When the mouthpiece is in use, the resilience of the material of the ferrule causes the cylinder and ring to firmly engage the walls of the bottle so that little or no liquid passes between the cylinder 23 and the inside wall of the bottle. Any liquid which passes therebetween is discharged on the tongue. As shown, tongue 22 is sufficiently long to overhang both edges of the outer flange of ferrule 21 to catch any liquid which may reach the edges.

In Fig. 8 is shown a mouthpiece which is intended for use with a bottle 31 having a relatively wide mouth. This mouthpiece includes a ferrule 32 which is of substantially the same shape and construction as the ferrule portion of the device shown in Figs. 2 and 3. However, the tongue 34 of this mouthpiece is integral with the inner flange of the ferrule and extends inside the ferrule and parallel to the axis thereof, as shown in Fig. 8, to provide means from which it is possible to drink directly from a bottle having a relatively wide mouth.

In Fig. 9 is shown a device having a ferrule 36 and a tongue 37 formed from separate pieces. The ferrule 36 is generally similar to the ferrule portion of the mouthpiece shown in Fig. 2, but is provided with an inner flange or cylinder 38 which terminates in a plurality of teeth 39. Teeth 39 are cut from the material of cylinder 38 and are normally bent outwardly from inner flange 38 so that when the mouthpiece is mounted on a bottle, the teeth 39 resiliently engage the interior of the mouth of the bottle. The ferrule 36 is split, as indicated at 39', so that the ferrule is resilient and can firmly engage the mouth of a bottle. The ferrule is provided with an opening 40 in the mouth thereof opposite the center of tongue 37. Opening 40 serves the same purpose as does the opening 18 of the device shown in Figs. 1-3 inclusive, and catches any liquid which may escape between cylinder 38 and the wall of the bottle.

In Fig. 10 is shown a mouthpiece 41. Mouthpiece 41 includes a ring 42 and a tongue 43 integral therewith. Ring 42 fits over and embraces the mouth of a bottle 44 with tongue 43 extending parallel to the axis thereof. Mouthpiece 41 70 may be formed of resilient plastic material or the like having sufficient resilience that, when the mouthpiece is mounted on the mouth of the bottle 44, the ring portion 42 resiliently engages the mouth of the bottle.

The mouthpieces shown in Figs. 1-9 inclusive are all formed of sheet material such as thin paperboard or the like. The material used in forming drinking cups and the like is suitable, and the mouthpieces may be sufficiently inexpensive to be discarded after use. The mouthpiece of Figs. 10 and 11, on the other hand, may be made of more durable material and may be cleaned and reused.

From the foregoing, it will be apparent to those skilled in this art, that various modifications and changes may be made in the illustrated embodiments of the invention without departing from either the spirit or scope thereof.

Having thus described my invention, what I claim as new and desire to secure by Letters Patent is:

1. A mouthpiece of sheet material for a bottle which comprises a ferrule having a cylindrical portion adapted to be received in the throat of the bottle and an annular return bend flange at its outer end adapted to receive the lip of the bottle, said flange and cylindrical portion being split longitudinally and being normally greater in diameter than the lip and throat, respectively, whereby upon insertion of the cylindrical portion in the throat and the flange over the bottle lip, the ferrule resiliently engages the throat and lip, and a spout integral with the outer flange of the ferrule and connected thereto by a return bend at the side of the ferrule opposite the split, the free end of the spout projecting substantially parallel to and in a direction opposite to the flange of the ferrule.

2. A one-piece mouthpiece of sheet material for a bottle which comprises an annular ferrule of channel shape in section having substantially coaxial inner and outer flanges and a web therebetween adapted to receive and embrace the mouth of the bottle, said ferrule being split and resilient and normally being of greater diameter than the bottle, whereby, when the ferrule is mounted on the mouth of the bottle, the inner flange of the ferrule firmly engages the inside of the mouth of the bottle, and a trough-like tongue integral with the outer flange of the ferrule and connected thereto by a return bend at the side of the ferrule opposite the split, the free end of said tongue projecting substantially parallel to and in a direction opposite to the flanges of the ferrule.

3. A mouthpiece in accordance with claim 2 characterized by the fact that there is an opening in the web of the ferrule at substantially the center of the tongue for discharge of liquid from between the bottle and the ferrule.
